UNITED STATES PATENT OFFICE

2,475,396

CASTING APPARATUS

Nathan Lester, Shaker Heights, Ohio, assignor
to Lester Engineering Company, Cleveland,
Ohio, a corporation of Ohio

Application October 10, 1946, Serial No. 702,456

3 Claims. (Cl. 22—68)

1

The present invention relating generally as indicated to a casting apparatus without regard to either the casting or molding material employed or the article formed thereby is, however, particularly concerned with the forming, for example, of electric motor armatures wherein a one-piece aluminum or other high heat conductive material skeleton in the laminated body of the armature effectively dissipates the heat generated in said body and serves as a frame for retaining the laminations in firm abutting relationship. Effective heat dissipation by such a skeleton, even though formed of a material such as aluminum which has a high thermal conductive constant compared to that of the iron laminations, is, nevertheless, largely dependent upon the forming of the skeleton so as to include a series of relatively thin webs and fins which present large heat dissipating surfaces per unit mass of metal.

Prior to the advent of the present invention, the forming of articles of the character indicated was considered impracticable for at least two reasons, viz. (1) because of the partial solidification of the metal in the small cross section mold cavities before being completely filled with metal, thereby producing porous castings with cold shuts and other defects, or (2) because in order to make sound castings without such defects, it was necessary to heat the mold to a temperature approaching that of the metal injected thereinto and then to cool the mold to effect solidification of the metal. The latter procedure, in addition to consuming a lot of time, entailed the added expense of employing elaborate heating and cooling equipment.

In further elucidating on the first reason above which refers to a "cold chamber" process, it can be seen that when the article to be cast is annular in form and includes many thin webs as does the armature herein disclosed, a "center shot" is not feasible because the molten material in the horizontally disposed injection chamber prematurely runs into the mold cavity and partially solidifies therein before the entire cavity can be filled. Such incomplete filling is especially undesirable in armatures of the character indicated in that the entire unit will be out of balance and the heat generated therein will be unevenly conducted away. Furthermore, cold shuts and other defects at critical points may weaken the skeleton to the point where portions thereof will be thrown off by centrifugal force and thereby cause serious damage to the surrounding motor housing. An "off-center" shot will, of course,

take care of the premature running of the material into the cavity but, on the other hand, the material has to be flowed long distances to the upper corners of the cavity and thus has a chance to partially solidify and impede complete filling of the cavity.

Accordingly it is one principal object of this invention to provide an apparatus by which articles of the character indicated can be efficiently made, said apparatus being characterized in that a "center shot" is rendered feasible.

It is another object of this invention to provide a method and apparatus by which articles of the character indicated can be rapidly produced without encountering the difficulties heretofore experienced.

Another object of this invention is to provide a casting method and apparatus incorporating a novel arrangement for assuring that the molding material in a heated and liquid state is continuously and quickly injected into the mold cavity so as not to permit cooling and partial solidification of portions thereof before the remaining portions are completely filled.

Additional objects and advantages of the invention will become apparent as the following description proceeds.

To the accomplishment of the foregoing and related ends, said invention then comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In the drawings:

Fig. 1 is a central vertical cross section view of a portion of one form of casting apparatus illustrating the separable die blocks, a portion of the injection chamber in communication with the mold cavity formed by said blocks and the ejector mechanism;

Fig. 2 is a view similar to Fig. 1 but on a smaller scale and illustrating more fully the injection chamber and the plunger reciprocable therein;

Fig. 3 is a transverse face view of one of the die blocks as viewed along the line 3—3, Fig. 1, with the cast article and sprue adaptor removed;

Fig. 4 is a perspective view of the armature formed by the apparatus illustrated in the foregoing figures;

Fig. 5 is a central vertical cross section view of the skeleton of the armature illustrated in Fig. 4

taken along a plane transverse to the axis of the armature with the laminated body omitted;

Fig. 6 is a perspective view of one form of sprue adaptor which affords communication between the injection chamber and the mold cavity;

Fig. 7 is a fragmentary cross section view taken along line 7—7, Fig. 1, illustrating more clearly the passage arrangement between the injection chamber and the mold cavity; and

Figs. 8 and 9 are perspective views of other forms of sprue adaptors.

Referring now to the drawings and first more particularly to Figs. 1, 2, 3, and 6 to 9, there is shown therein only those portions of the apparatus with which the present invention is concerned, viz. the combination of a horizontally disposed injection cylinder with separable die blocks which form a mold cavity therebetween.

As illustrated, the mold cavity for producing an article of the aforesaid character is formed between the several die blocks 1, 2 and 3, die block 1 being preferably carried by a fixed platen not shown and die blocks 2 and 3 together being preferably carried by a movable platen not shown. In effect, the intermediate die block 2 is an integral part of die block 3, but in order to facilitate making of the mold cavity, such die blocks 2 and 3 are separately made and then secured together. Although the movement of the die blocks 2, 3 toward and away from die block 1 is usually guided by sliding the movable platen on suitable ways and/or tie bars associated with the frame of the machine as for example illustrated in Lester et al. Patent No. 2,365,282 dated December 19, 1944 and Lester Patent No. 2,309,460, dated January 26, 1943, it is preferred that additional means be employed for the purpose of accurately locating the die blocks 1 and 2, 3 relative to one another at least when brought together. Such additional locating means in the present case comprises dowels 4 fixed in die block 1 and having close sliding engagement in bushings 5 fixed in die block 2.

Associated with the die block assembly 2, 3 is an ejector mechanism comprising an ejector plate 6 having several push pins 7 projecting therefrom through the die blocks 2, 3 with the ends thereof engaging the parting line face of die block 1 and ejector pins 8 through die block 3 projected into the mold cavity and adapted to engage the molded article and displace the same from the mold cavity. The ejector plate 6 is actuated in one direction through a plate 9 provided with a gear rack 10 in mesh with a rotatably supported pinion 11 and in the other direction by engagement of the parting line face of die block 1 with the ends of the push pins 7. In operation, after the die blocks 1 and 2, 3 have opened, the gear 11 is rotated counter-clockwise, as viewed in Figs. 1 and 2, to cause the ejector plate 6 to be urged toward the left relative to die block 2, 3 to thereby displace the molded article from the die block 2, 3 or at least free the article so that it can be readily removed.

The die block 1 as aforesaid is preferably mounted in a fixed platen and has fitted into a central opening therethrough a plunger bushing 12, said bushing forming an extension of the injection cylinder 13 fixed to the die block 1. The injection cylinder 13, as best shown in Fig. 2, comprises an elongated horizontally disposed cylinder having a lateral opening 14 through which molding material in a liquid state can be supplied into the injection chamber defined by the inner walls of the cylinder and plunger bushing.

A plunger 15 reciprocable in cylinder 13 and bushing 12 when moved toward the right from the solid line position shown in Fig. 2 will obviously first close the lateral opening 14 and then, in a manner to be explained, force the molding material from the injection chamber into the mold cavity.

The molded article 16 herein illustrated comprises the laminated body made up of a plurality of thin plates 17, and annular rings 18 at each end of said body integrally connected to one another by thin webs 19 which pass through generally radially disposed slots in the body, such slots extending transversely of the plates 17 from one end to the other of the body. Projecting from each annulus 18 are a plurality of fins 20. The laminated body has a central opening 24 therethrough into which a shaft, not shown, is adapted to be press fitted or otherwise secured to form trunnions for rotatably supporting the same. The armature illustrated is intended for use in a motor of the rotating field type and, of course, as is well known, the laminated body minimizes hysteresis and eddy current losses. Plates 17 are of iron and each is preferably about .025 inch thick and preferably has a thin heat-resisting insulating coating or film on its opposite faces whereby the plates in assembled relation are insulated from one another. Although such laminated structure does materially reduce the hysteresis and eddy current losses, as compared with a solid iron body, there is yet considerable heat generated in such body. The reason for incorporating the webs 19, the annuli 18 and the fins 20 in such laminated body is to dissipate such heat. This can be most effectively done by making the aforesaid elements 18, 19 and 20 from a high heat conductive material and proportioning the same so as to present large heat absorbing and radiating areas. In this way, the heat generated in the laminated body is picked up by the webs 19 and conducted to the annuli 18 and fins 20 from which it is effectively dissipated during rotation of the armature. Of course, in some cases it may be desirable to omit the fins on either or both of the annuli 18. Furthermore, it is to be noted that the webs 19 are inclined relative to the axis of the body whereby still greater heat radiating areas are provided. The elements 18, 19 and 20, being integrally connected, constitute a skeleton, see Fig. 5, which, in addition to effectively dissipating the heat generated in the laminated body, serves as a framework to tie the plates 17 together as a single unit. While it is preferred that this skeleton be made of aluminum because of its light weight (approximately $\frac{1}{3}$ that of iron) and good heat conducting properties (approximately 3 to 5 times that of iron) and low melting point (less than $\frac{1}{2}$ that of iron), there are other metals such as copper, gold, magnesium, silver, etc. which might be satisfactorily used. However, while the aforesaid metals may have good heat conducting properties, they may be undesirable from the standpoint of high melting point, excess weight, prohibitive cost, etc. In addition to the aforesaid metals, it is also conceivable that many metal alloys could be satisfactorily used and possibly certain plastic materials particularly those of the thermosetting type.

The mold cavity for forming the above described armature is essentially in three parts, namely, the cavities for the annuli 18 and fins 20 in die blocks 1 and 3, and the cavity in die block 2 surrounding the laminated body. The cavity in die block 1 is formed in a chamber disposed concentrically about the plunger bushing 12, in

which chamber the slotted insert 21 defines with die block 1 and plunger bushing 12 one annulus 18 and the series of fins 20 projecting therefrom. An identical insert 21 secured in an annular chamber defined between die block 3 and a centrally projecting part 22 forms the other annulus 18 and series of fins 20. The webs 19 are defined by slots extending from end to end of the laminated body and the central opening 23 in die block 2 provides an annular chamber into which molding material may flow, such material being usually machined off in finishing the article. Opening 23 is preferably slightly tapered so as to be larger in diameter at its left-hand end to thus facilitate removal of the molded article. It is to be noted that the ends of the slots defining webs 19 are in communication with the cavities defining the annuli 18 and that such latter cavities are in communication with the cavities defining the fins 20. Likewise, such slots are in communication with the annular chamber surrounding the body.

Surrounding the mold cavity in each die block is a passage 25 terminating at its ends in an inlet 26 and an outlet 27, through which passage a suitable cooling medium such as cold water may be circulated to prevent excessive heating of the die blocks and thus provide a relatively cool mold cavity.

Having thus described the mold cavity, reference will now be made to the means for holding the plates 17 together during molding and the means for establishing communication between the injection chamber and the mold cavity. As to the former, the plates 17 are snugly fitted over a shaft 28. The projecting end of shaft 28 is adapted to be slip fitted into an opening in the part 22 in die block 3 in order to centrally locate the body in the cavity. As to the latter, the other end of shaft 28 has the reduced end portion 44 of a sprue adaptor 29 slip fitted thereinto. Said sprue adaptor has a generally frusto-conical head which is adapted to extend into a corresponding frusto-conical bore in the end of the plunger bushing 12 and to make sealed or substantially sealed engagement therewith when the die blocks 1 and 2, 3 are closed. A portion of the outer periphery of the sprue adaptor is cut away as at 30 to thus define with the wall of the bore in the plunger bushing 12 a part annular chamber. Such part annular chamber, for a reason which will be presently explained, is disposed at the upper portion of the plunger bushing bore. The right-hand end of the plunger bushing 12 which is adjacent one end of the laminated body is likewise provided with a cut away portion 31 terminating at its outer periphery in several channels 32. In register with channels 32 are channels 33 in the insert 21, such latter channels leading into the annular chamber defining the annulus 18. The cut away portion 31 is in register with the cut away portion 30 and, therefore, it can be seen that molding material from the injection chamber can be forced directly into the mold cavity through the cut away portions 30 and 31 and the channels 32 and 33.

The sprue adaptor described above is that illustrated in Figs. 1, 2, 6 and 7. The sprue adaptor 35 illustrated in Fig. 8 is not only peripherally cut away at 36 but has a reduced rearward end 37 either all the way around as shown or only part-way around if desired. Such reduced end 37 defines with the laminated body and the plunger bushing 12 an annular chamber having a portion thereof disposed below the normal level

of molten material in the cylinder 13. Radially outward of such annular chamber, the plunger bushing 12 and the insert 21 will be provided with further channels 32 and 33 to thus assure uniform and quick distribution of the molten material to all parts of the mold cavity when the plunger 15 is moved to the right as viewed in Fig. 2. The end of sprue adaptor 35 is further reduced as at 44 to provide an axial projection adapted to have a sliding fit within shaft 28.

The sprue adaptor 38 illustrated in Fig. 9 has a cut away portion 39 which, adjacent the rearward end of the sprue adaptor terminates in oppositely extending grooves 40 and 41, such grooves 15 extending only partway around the periphery. The flange defined between the grooves 40 and 41 and the rearward end of the sprue adaptor is cutaway as at 42 and 43 to provide diametrically opposed passages in communication with several 20 diametrically opposed channels 32 and 33 in the plunger bushing 12 and insert 21 respectively. With this sprue adaptor the molten material, when the plunger is moved toward the right in Fig. 2, will flow through cutaway portion 39, 25 grooves 40 and 41, passages 42 and 43 and channels 32 and 33 into the mold cavity. By providing such large size diametrically opposed passages leading to the mold cavity, the molten material can be quickly and uniformly flowed into 30 the mold cavity. Sprue adaptor 38 also has a reduced end portion 44 adapted to slidably fit within the shaft 28.

The relationship of the size and location of the injection chamber to the passage between the injection chamber and the mold cavity and to the mold cavity is such that molding material in the injection chamber in volume sufficient to fill the cavity, the passage and a small portion of the injection chamber, as indicated by the dotted line 34 in Figs. 1 and 2, can only communicate with the mold cavity upon movement of the plunger 15 toward the right, as viewed in Figs. 1 and 2, to first close the lateral opening 14 and raise the level of the molding material up to such passage. With an arrangement such as this, no molding material can preliminarily flow into the relatively cool mold cavity and solidify therein prior to the mold cavity and the passage leading thereto being filled. In fact, the molding material is rapidly and continuously shot into the mold cavity under pressure so as to completely fill the same before portions thereof have partially solidified. Such quick shot action eliminates forming of cold shuts in the casting. Furthermore, such metal solidifies so rapidly in the relatively cool mold cavity, that the die blocks can be separated and the completed article removed without having to wait any appreciable length of time. A further feature flowing out of 55 the above arrangement is that the material solidifies and cools before the die blocks and laminated body have a chance to appreciably heat up and expand, whereby when the webs 19 cool and contract, such contraction is effective to draw the annuli 18 firmly against the laminated body and thus urge the plates 17 into firmer engagement with one another.

In operation of my apparatus, the laminated body is first placed between the die blocks 1 and 2, 3 with the shaft 28 extended into the part 22 and the sprue adaptor (29, 35, or 38) extended into the plunger bushing 12. The die blocks 1 and 2, 3 are then moved toward one another to closed position, at which position the ends of part 75 22 and bushing 12 securely clamp the laminated

body therebetween. Molding material in a liquid state and in volume sufficient to fill the mold cavity, the passage leading thereto and a small portion of the injection chamber is then poured into the injection chamber through the lateral opening 14. The level of such volume of molding material is, as clearly illustrated in Fig. 2, well below the cutaway portion of the sprue adaptor so that no material has yet been flowed into the mold cavity. The plunger 15 is then moved toward the right to close the opening 14 and simultaneously raise the level of the material in the injection chamber. After the opening 14 has been closed, continued movement of the plunger will raise the level of the material up to the sprue adaptor passage and channels 32 and 33 and permit the material to flow into the mold cavity. The movement of the plunger 15 is relatively rapid and continuous whereby the mold quickly fills up. When the mold cavity and passages are filled, the pressure exerted by plunger 15 will effect a compacting action on the material and further force it into all of the corners of the cavity. Inasmuch as the material quickly solidifies in the cool mold cavity, the plunger can be immediately withdrawn and the die blocks separated to eject the completed article. The slug of material in the channels 32, 33 and in the sprue adaptor passages and in the injection chamber between the left-hand end of the sprue adaptor up to the dotted line 34 can be cut off at the inner periphery of the annulus 18. With such slug removed, the sprue adaptor can then be removed, as can the shaft 28. The armature so formed can then be fitted with the shaft forming the trunnions on which it can be rotatably mounted in a motor housing. If the opening 23 in die block 2 is larger than the laminated body as shown in Fig. 1, the layer of material around the periphery of the laminated body can be removed if desired in a lathe or like machine tool. It is to be observed that the clamping of the laminated body between the die blocks 1 and 3, as described above, assures that the plates 17 will be compacted together, whereby no material can be squirted between them during the casting operation.

Other modes of applying the principle of the invention may be employed, change being made as regards the details described, provided the features stated in any of the following claims or the equivalent of such be employed.

I therefore particularly point out and distinctly claim as my invention:

1. A pressure casting apparatus for forming articles, said articles having a cylindrical body and an annular ring portion with circularly arranged radial fins projecting axially therefrom, comprising separable die blocks forming a chamber for said body and a mold cavity corresponding with such annular ring portion, one of said die blocks being formed with a bore therethrough coaxial with such cavity, a tubular sprue bushing fitted within such bore, one end of such bore being enlarged whereby to form an annular recess with said sprue bushing, a one-piece tubular insert snugly fitted in such recess having the end thereof which is adjacent such cavity formed with slots radially therethrough corresponding with such fins, one end of said bushing and insert being formed with registering channels leading from within the former into such cavity, a horizontally disposed injection cylinder co-axial with such cavity and engaged with the other end of said bushing, the other of said die blocks being

formed with a central opening coaxial with said sprue bushing, a shaft adapted to support said body therearound and having one end slidably fitting within such opening, a plug projecting axially into said bushing and including an axially extending groove in its upper surface defining with said bushing a passage leading from within said cylinder to such channels, said plug having a sliding fit with the other end of said shaft, and a plunger movable in said cylinder to force material to be cast from said cylinder through said passage and channels into such cavity and thence from such cavity into the slots of said insert.

2. A pressure casting apparatus for forming articles, said articles having a cylindrical body and an annular ring portion with circularly arranged radial fins projecting axially therefrom, comprising separable die blocks forming a chamber for said body and a mold cavity corresponding with such annular ring portion, one of said die blocks being formed with a bore therethrough coaxial with such cavity, a tubular sprue bushing fitted within such bore, one end of such bore being enlarged whereby to form an annular recess with said sprue bushing, a one-piece tubular insert snugly fitted in such recess having the end thereof which is adjacent such cavity formed with slots radially therethrough corresponding with such fins, one end of said bushing and insert being formed with diametrically opposed channels leading from within the former into such cavity, a horizontally disposed injection cylinder co-axial with such cavity and engaged with the other end of said bushing, the other of said die blocks being formed with a central opening coaxial with said sprue bushing, a shaft adapted to support said body therearound and having one end slidably fitting within such opening, a plug projecting axially into said bushing and including an axially extending groove in its upper surface defining with said bushing a passage leading from within said cylinder to such channels, said plug having a sliding fit with the other end of said shaft, such groove terminating in diametrically opposed branches communicating with such channels, and a plunger movable in said cylinder to force material to be cast from said cylinder through said passage, branches, and channels into such cavity and thence from such cavity into the slots of said insert.

3. A pressure casting apparatus for forming articles, said articles having a cylindrical body with a skeleton cast thereabout, which skeleton includes an annular ring portion at each end of said body connected together by circularly arranged radially disposed webs through said body and circularly arranged radial fins projecting axially from each such ring portion, comprising separable die blocks formed with opposed central hollow, coaxial projections adapted to engage the ends of said body and thereby clamp the latter therein, said die blocks together with such projections and body defining annular chambers at each end of such body corresponding with the aforesaid annular ring portions of such skeleton, a tubular insert in each such chamber each having the end thereof which faces the respective chamber formed with slots radially therethrough corresponding with such fins of such skeleton, the end of one of such projections and the associated insert being formed with registering channels communicating with the associated chamber, an injection cylinder co-axial with said die blocks having communication with said one of such projections, a shaft central-

ly through such body adapted to support the latter and having one end slidably fitting within the other of such projections, a plug projecting axially from said body into said one of such projections and including an axially extending groove in its upper surface defining with said one of such projections a passage leading from within said cylinder to such channels, said plug having a sliding fit with the other end of said shaft, and a plunger movable in said cylinder to force material to be cast from said cylinder through such passage and channels into the associated chamber and thence from such chamber into the slots of one of said inserts, through said body into the other of such chambers and into the slots in the other of said inserts.
